UNITED STATES PATENT OFFICE.

JEREMIAH PARK, OF MONTANDON, PENNSYLVANIA.

END-BOARD FOR WAGONS.

SPECIFICATION forming part of Letters Patent No. 248,498, dated October 18, 1881.

Application filed August 13, 1881. (No model.)

To all whom it may concern:

Be it known that I, JEREMIAH PARK, of Montandon, in the county of Northumberland and State of Pennsylvania, have invented a new and useful Improvement in Wagon-Body Attachments; and I do hereby declare that the following is a full, clear, and exact description of the same, reference being had to the accompanying drawings, forming part of this specification, in which—

Figure 1 is a side elevation of a wagon-body with my improved attachment. Fig. 2 is a plan view of the same, and Fig. 3 is a vertical longitudinal section in the line xx of Fig. 2.

My invention relates to improvements in wagon-body attachments; and it consists of an attachment or box provided with inclined sides of the same height as the wagon-body, and having a slide in its inclined bottom, which attachment can be secured to or removed from either end of the body, as desired, whereby the capacity of the wagon-body is increased without increasing its height, and commodities—such as corn, fruit, vegetables, &c.—can more quickly be unloaded from the wagon by moving out the slide and letting the corn or other commodity fall through, thus allowing the bottom of the bed of corn or other commodity in the wagon to be more quickly reached for the action of the scoop or shovel than if picked out by hand from the wagon-body, as hereinafter more fully set forth.

In the accompanying drawings, a represents a wagon-body of the usual construction, provided with a staple, b , in each of its sides near its rear end.

c represents my improved attachment, provided with inclined sides $d d$, each preferably of the form of a right-angled triangle the altitude of which is the height of the wagon-body.

The inclined bottom e of the attachment is provided with a longitudinal opening, g , preferably at its middle, in which reciprocates a slide, h , adapted to be slid back and forth in the opening. The inner ends of the longitudinal pieces composing the bottom of the attachment and the inner end of the slide are beveled,

so as to form no obstruction where they meet the upper surface of the bottom of the wagon-body.

$k k$ represent hooks pivotally secured to the sides of the attachment, and adapted to engage with the staples $b b$ in the sides of the wagon-body, whereby the attachment can readily be secured to or detached from the body, 55 when desired.

The attachment is preferably secured to the rear end of a wagon-body by removing the tail-board, although, if desired, it may be applied to the front end of the body by removing the 60 front board of the body.

By this construction it will be seen that the capacity of the wagon-body will be increased without increasing the height of the sides, which increase in the height of the sides necessitates greater labor in loading the wagon. 65

The attachment also can be readily secured to and easily removed from a wagon-body, and by removing the slide the corn or other articles over the opening in the bottom of the 70 attachment can readily be removed from the body, falling by gravity into a basket or other receptacle arranged to receive them.

Farmers, to unload corn, potatoes, &c., must pick out of the wagon bed or box at the end 75 several bushels, in order to reach the bottom of the bed, before they can use the scoop, on account of the perpendicular end-board.

By my invention, it will be observed, much time and trouble are saved by withdrawing the 80 slide and allowing the articles to fall through, and the bottom of the bed of corn, &c., to be reached at once by the scoop.

I claim as my invention—

The combination, with a wagon-body, a , having staples $b b$ in its sides, of the attachment c , provided with inclined sides $d d$, having hooks $k k$, bottom e , having opening g , and slide h , substantially as described, and for the purpose set forth. 85

JEREMIAH PARK.
